Specification of Letters Patent.

Patented Aug. 5, 1913.

Application filed October 18, 1912. Serial No. 726,519.

To all whom it may concern:

Be it known that I, JACOB J. BUSENBENZ, a citizen of the United States, residing at Chicago, in the county of Cook and State of Illinois, have invented a new and useful Improvement in Clocks, of which the following is a specification.

My present invention is an improvement in the driving mechanism of Letters Patent No. 973,854, granted to me October 25th, 1910, in which a helical spring connecting a primary motor and a train of gears surrounds a core containing an enlargement, the spring constantly undergoing contraction, by the power of the motor, about the core and unwinding at its train-driving end, with power, controlled by the breaking or choking action of the enlargement, only about sufficient to drive the train. Thus, however powerful the primary motor may be, the regulating action of the core-enlargement prevents its being used to a greater extent than is required to overcome the resistance of the train. In this way, when, as is my practice, this device, which is in the nature of a differential governor, is positioned immediately below the hour-shaft, it divides the clock, as it were, into two distinct units, namely, the train from the center arbor to the escape-wheel, with the pallet as the time-measuring unit, while the train below the center arbor forms the motor or power unit.

The object of my present improvement is to provide means for regulating with desirable accuracy the tension of the train-driving section of the spring to that required for driving or overcoming the resistance of the train.

In the accompanying drawings, Figure 1 is a broken view in sectional elevation of a clock embodying my improvement; Fig. 2 is an enlarged broken view in section showing the improved regulating means; Fig. 3 is a view in side elevation of the expandable and contractible core-section; Fig. 4 is an end view of the same, and Fig. 5 is a view in side elevation of the stem-device for expanding and contracting the core.

As in the aforesaid patent, the motor 5 is shown as two similar flat-spring coils carrying corresponding gears 6 and 7 to mesh with an interposed pinion 8, part of the clock-train 9 being illustrated with shafts 10 and 11 carrying, respectively, the hour and minute hands 12 and 13; and the pinion 8 is

journaled on one end of a cylindrical core 14 provided nearest the motor with the power-reducing enlargement 15, the core having journaled on its opposite end a gear-wheel 16 meshing with the first gear of the train, and being surrounded by the helical spring 17 secured at its opposite ends, respectively, to a sleeve extending from the pinion 8 and a sleeve extending from the gear-wheel 16. The operation is the same as described in said patent, namely, the recoil-force of the wound motor-springs in unwinding, turns the pinion 8 in one direction, thereby tensioning the spring 17 throughout its length about the core until further tensioning thereof is obstructed by the enlargement 15, and thus constantly winds the spring 17 at one end while it is unwinding correspondingly at the opposite end to drive the train, the enlargement reducing the excessive power of the motor to that required for driving the train.

As will be seen, the internal diameter of the spring 17 and the external diameter of the core have a direct relation in the calibration of the force required in the time-measuring train, the force being increased in proportion as these diameters approach each other, being zero when they coincide at the enlargement, so that only the power stored in the spring between the enlargement and the gear 16 is active. For different trains, therefore, to which this patented governor may be applied, the tension of the driving-section of the spring 17 must be appropriate, and to render it so by regulation I provide means for expanding and contracting the core-enlargement, of the following-described preferred construction.

The core 14 is divided transversely, through its enlargement, forming a section 14¹, which is hollow, and a section 14², which is hollow to the point 14³, adjacent to which it is internally threaded. The section 14², which is of sufficiently resilient metal, as brass, is split longitudinally into four equal sections, the splits extending about to a point α from the extremity of the enlarged end of the section, which is internally beveled at its mouth, as shown at 18. A stem 19, provided on its outer end with a hand-wheel 20, fits rotatably in the core-section 14¹, beyond which it is formed with a wedging section 19¹ to engage the bevel 18, this section tapering to a reduced section 1

19² in the core-section 14², having a thread 19³ on its end-portion to engage the threads in that section.

By turning the stem 19 to screw it inwardly or outwardly, resultant advancement or withdrawal in the core-section 14², at the bevel 18, of the wedge 19¹ causes expansion or contraction of the enlargement, thereby reducing in the one case and increasing in the other the extent to which the motor can contract the spring about the enlargement and, accordingly, the tension of the train-driving spring-section. This adjustment of the driving-tension of the spring 17 is very readily effected by the described means provided for the purpose, whether my patented device, equipped therewith, be applied, as it may, to a clock-train or other gear. I realize, however, that considerable variation is possible in the details of construction of my present improvement thus specifically shown and described, and I do not intend by illustrating a single, specific or preferred form, to limit my invention thereto; my intention being in the following claims to claim protection upon all the novelty there may be in the device as broadly as the state of the art will permit.

What I claim as new and desire to secure by Letters Patent is—

1. In combination, a primary motor, a train of gears, a core, a helical spring about the core connected at one end with said motor and at its opposite end with said train to be contracted about the core by the power of the motor, regulating means coöperating with the spring between its ends to form and limit the extent of tensioning the train-actuating section thereof, and means for increasing and decreasing, at will, the limit of tensioning said section.

2. In combination, a primary motor, a train of gears, a core provided with an enlargement between its ends, a helical spring

about said core and enlargement geared at 45 one end to said motor and at its opposite end to said train, and means for expanding and contracting, at will, said enlargement.

3. In combination, a primary motor, a train of gears, a core provided between its ends with an enlargement formed of resilient sections, means for spreading said sections to expand the enlargement against the contracting tendency of its sections, and a helical spring about said core and enlargement geared at one end to said motor and at its opposite end to said train.

4. In combination, a primary motor, a train of gears, a hollow core divided between its ends into sections, one section having a longitudinally-split enlargement forming resilient sections thereof, a handle-equipped threaded stem in the core working into said split section thereof and provided with a wedge engaging said resilient sections, and a helical spring about said core and enlargement geared at one end to said motor and at its opposite end to said train.

5. In combination, a primary motor, a train of gears, a hollow core divided between its ends into two sections, one section having a longitudinally-split enlargement on one end forming resilient sections thereof and containing an inwardly-tapering 75 mouth and screw-threads at its inner end, a handle-equipped stem rotatable in said core-sections, threaded at its inner end to engage said screw-threads and provided with a tapering section between its ends to coöperate with said mouth, and a helical spring about said core and enlargement geared at one end to said motor and at its opposite end to said train.

JACOB J. BUSENBENZ.
